[57] CLAIM

The ornamental design for a potato carton, as shown and described.

DESCRIPTION

FIG. 1 is a perspective view of a potato carton in open position, showing our new design;

FIG. 2 is a perspective view thereof in closed position;

FIG. 3 is a top plan view thereof;

FIG. 4 is a bottom plan view thereof;

FIG. 5 is a front elevational view thereof;

FIG. 6 is a rear elevational view thereof; and

FIG. 7 is an elevational view of one end thereof, the opposite end being a mirror image of the figure shown.
